UNITED STATES PATENT OFFICE.

JEAN NADAL, OF PARIS, FRANCE.

STUD OR FASTENING FOR SHIRT-WRISTBANDS, &c.

SPECIFICATION forming part of Letters Patent No. 528,339, dated October 30, 1894.

Application filed October 2, 1893. Serial No. 487,004. (No model.)

To all whom it may concern:

Be it known that I, JEAN NADAL, of the city of Paris, France, have invented Improvements in Studs, Buttons, or Fastenings for 5 Shirt Wristbands or Cuffs and the Like, of which the following is a full, clear, and exact description.

My invention relates to an improved stud, button or fastening for shirt wristbands, or 10 cuffs and other articles of wearing apparel in which the disk constituting the back is formed in two halves capable of being expanded to secure the stud or button in position and of being contracted or brought into line with the 15 pillar to facilitate the insertion of the button in the button hole or its withdrawal therefrom, and my said invention consists in the combination and arrangement of parts hereinafter described and set forth in the claims. 20 Reference is to be had to the accompanying drawings, forming part of this specification, wherein—

Figure 1 represents a side elevation of the button showing the narrow side of the pillar or shank, the folding back being expanded, and Fig. 2 is a plan view of the same, while Fig. 3 is a sectional view of the button on line 3—3 of Fig. 2. Fig. 4 is a fragmentary detail view partly in section of the top of the pillar 30 taken on line 4—4 of Fig. 2. Fig. 5 is a longitudinal sectional elevation of the pillar showing the back folded in line with the shank or pillar. Fig. 6 is a broken-away longitudinal sectional elevation taken at right angles to Fig. 5. Fig. 7 is a fragmentary detail view of a portion of the button looking in the direction of the arrow in Fig. 3. Fig. 8 is a cross-section of a modification of my invention. Fig. 9 is a section of the same taken on line 35 9—9 of Fig. 8 and corresponding to a section on line 9—9 of the form shown in Fig. 2. Fig. 10 is a sectional view of the same showing the wings closed; and Fig. 11 is a detail view of a part to be described.

Referring to the drawings, the button is composed of the head *j*, the hinged back made in halves *d d*, and the pillar *b* formed in one with the flange or disk *a*. The head *j* and the pillar *b* are revoluble with relation to each 40 50 other. The pillar is preferably of oval form in cross-section to conform, as near as possible to the shape of the button-hole and it is

provided at the end opposite to disk *a* with ears *f* in which the pivots *c* on knuckles *e* of the two semi-circular wings *d d* constituting 55 the back are mounted.

g is the shank of a T-shaped piece which is received within the pillar *b* and passes through a spring *h* which is adapted to be compressed between the head *j* and the disk 60 *a*. This shank *g* of the T-shaped piece, after passing through the spring *h* extends into the head *j* to which it is keyed, by being flattened at *i* and fitting in a corresponding hole in the said head *j* so as to prevent the two 65 parts from turning independently of one another, or it may be fastened in any other desirable manner. The shank *g* is secured in the head *j* by a fork *k* slipped in notches made in the end *i* of the shank, or a cross-pin 70 passing through the end of the shank or other analogous device may be employed.

The wings *d d* constituting the folding back are operated by means of the T-shaped piece, (which may be turned in either direction,) 75 the shank *g* of which is rigidly connected with the head *j* as already described. The knuckle *e* of the hinge of the wings *d* is formed with a central aperture *l* (see Fig. 2) for the shank *g* to pass through and the knuckle is cut away 80 at *m m* to form suitable cam surfaces with which the arms *n n* constituting the head of the T-piece come in contact as the T-piece is rotated with relation to pillar *b*, so as to cause the wings *d d* to gradually close until they 85 meet and form virtually a continuation of the pillar *b*. When the wings are in this position the arms *n n* bear upon the flat shoulders *o* (Fig. 10) of the knuckle and by the pressure of the spring *h* retain the wings in 90 this position. (See Fig. 5.) By reversing the action or by continuing to rotate the head *j* the arms *n* will be disengaged from the shoulders *o*, and in passing over the cam surfaces *m* will open out or expand the wings. When 95 the T-piece is turned so that its arms *n n* occupy a position at right-angles to the hinges, the arms enter a recess or notch *p* in the face of each wing *d* and are thus locked so as to hold the wings open. The resistance necessary for preventing the turning of the pillar when turning the head of the stud is afforded by the button-hole.

In using the button, the head *j* is rotated

upon the pillar *b* either for the purpose of expanding the wings *d d*, when the stud or button is to be secured in position on the cuff, or for closing the two wings face to face to allow of their being passed through the button hole, when inserting or removing the stud.

Figs. 8 to 11 represent a modified arrangement in which the wings forming the back of the stud or button are caused to close toward each other and retained in that position by means of springs *r* contained within the pillar *b*. Whatever kind of spring be employed it must not in any way prevent the insertion or impede the action of the T-shaped piece which serves to cause the closing and expanding of the wings as before.

In Fig. 8 two steel wire springs are shown mounted within the pillar, toward either side thereof, so as not to interfere with the hinge or T-shaped piece.

The employment of springs it will be understood is optional. When they are not used the wings may be closed by simply drawing them through the button-hole after the T-shaped piece has been placed parallel with the hinge. Instead of each wing being separately hinged the hinge by which they are connected to the pillar may be common to both.

In the modification represented in Figs. 8 to 11 the pillar *b* is hollow and provided with a cross-bar *u* forming a bearing for the T-shaped piece which passes through a central aperture therein and is supported upon said cross-bar by a collar *x*. *r r* are the springs for acting on the hinged wings *d d*. The head *j* of the stud is recessed to receive a spring *h* and plate *y* as before, the plate being provided with cams or studs *z*, said plate having a square aperture *z³* (see Fig. 11) through which a squared part *z²* of the shank *g* passes, so that the two turn together.

When the wings *d d* are expanded, as in the modification illustrated in Figs. 8 to 11, the studs *z* are forced into the recess *z'* see Fig. 9 or hollow portion of the pillar by the spring *h* so as to lock the wings in position, when open.

When the wings are to be closed together, as illustrated in Fig. 10, the head of the button or stud is given a quarter turn whereby the projections *z z* are moved away from the recess compressing the spring and bearing against the under side of the disk *a* of the pillar. In this position the head of the T-shaped piece is parallel with the hinges of the wings which are brought to the position shown in Fig. 10, by the springs *r*.

I do not limit myself to the constructions shown and described, it being obvious that various modifications might be made without departing from the spirit of my invention.

What I claim, and desire to secure by Letters Patent, is—

1. In a cuff button, the combination of a pair of hinged wings *d* each having two cams *m* formed thereon, a pillar *b* supporting the wings, a head *j*, a shank *g* attached to the head and passing through and revolving freely in the pillar *b*, the said shank *g* having a cross-bar *n* to engage the cams *m* in the wings *d*, whereby the wings are opened and closed by giving the head one complete rotation, substantially as described.

2. In a cuff button, the combination of a pair of hinged wings *d* having cams *m*, a pillar *b* supporting the wings, a head *j*, a shank *g* attached to the head and passing through and revolving freely in the pillar *b*, the said shank *g* having a cross-bar *n* to engage the cams *m* in the wings *d*, whereby upon rotating the head the wings will be opened, together with a spring connected to the wings for automatically restoring the same to position when the stem has been rotated to free the cross-head from engagement with the cams, substantially as described.

The foregoing specification of my improvements in studs or fastenings for shirt wristbands or cuffs and the like signed by me this 16th day of September, 1893.

JEAN NADAL.
